(57) **CLAIM**

The ornamental design for a multifunction adapter, as shown and described.

DESCRIPTION

FIG. 1 is a front, right, bottom perspective view of a multifunction adapter;

FIG. 2 is a front, right, top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front, right, bottom perspective view thereof, shown in an alternate position.

The broken lines in the figures depict portions of the multifunction adapter that form no part of the claimed design.

1 Claim, 9 Drawing Sheets
